WILLIAM HOWARD RENNIE, OF VANCOUVER, BRITISH COLUMBIA, CANADA

CAN-WASHING MACHINE

Application filed April 15, 1929. Serial No. 355,348.

My invention relates to improvements in can washing machines which are particularly adapted for use in canneries, packing plants and the like.

5 The objects of the invention are to provide means for automatically receiving cans from a conveyor for scrubbing their opposing ends and their peripheral walls to wash away any of the contents which may have spilled thereover during the prior filling and sealing process, so that they are delivered for labeling in perfectly clean condition.

The invention consists essentially of a circular guide in which is rotatably mounted 15 a circular brushing element for scrubbing the side walls of the cans and further brushes which are adapted to wash the ends of the cans, as will be more fully described in the following specification and shown in the 20 accompanying drawings, in which:—

Fig. 1 is a plan view of the invention with a portion of the drive wheel cut away to expose the circular brushing element.

Fig. 2 is a sectional view taken on the line 25 2—2 of Figure 1.

In the drawings like characters of reference indicate corresponding parts in each figure.

The numeral 1 indicates generally a horizontal conveyor chain adapted to be driven in the direction indicated and which is adapted to extend slightly above the bottom level of a pair of troughs 2 and 3.

The troughs 2 and 3 are provided with side 35 walls 4 and are curved at their adjacent ends as at 5 and 6 to deflect the cans from the conveyor trough 2 to the machine and from the machine to the conveyor trough 3.

The numeral 7 indicates a frame supported 40 upon legs 8 connected together by transverse members 9 at the intersection of which a vertical driven shaft 10 is journaled. The frame 7 is arcuate in form and consists of upper and lower members 11 having opposed rebates 12 on their inner peripheral edges, the purpose of which will hereinafter appear.

Secured upon the shaft 10 is a wheel 13 having a rim 14 from which upper and lower flanges 15 extend. The opposed peripheral edges of said flanges are rebated as at 16 and

serve with the rebates 12 of arcuate frame members 11 to form guides and supports for cans to be cleaned. Fitted between the flanges 15 of the wheel 13 is a brushing element 17 consisting preferably of a plurality of segmental brushes 18 with their bristles projecting outwards to engage the side walls of the cans with a brushing or wiping contact as the wheel 13 rotates in the direction indicated. The brushes 18 are clamped in position between the flanges 15 with set screws 19 and are forced outwards from the rim 14 as may be required to take up wear by adjusting screws 20 extending through said rim.

Extending inwards from the upper and lower members 11 of the arcuate frame 7 are brackets 21 supporting brushes 22 having their bristles facing each other and which are so adjusted as to engage the top and bottom closures of the can. The brushes 22 are arranged in sets and are spaced apart around the interspace between the wheel 13 and the arcuate frame members 11 so as to permit the mounting of a plurality of curved pipes 23 having orifices 24 shown in dotted line, along one side so as to direct the water onto the cans as they pass around the machine. The pipes 23 are connected by branch lines 25 to a suitable water supply.

Having thus described the several parts of my invention I will now briefly explain its operation.

The water is first turned on to supply a suitable spray through the spray pipes and as cans are carried along on the conveyor chain 1 the cans in the curved portion of the trough 2 are thrust into contact with the rebates 16 of the wheel 13 against the brushing element 17 and the rebates 12 of the upper and lower arcuate frame members 11. The wheel 13 rotating transmits a reverse rotational motion to the cans, the rotation being assisted also by the wheel flanges 15 moving within the upper and lower arcuate frame members. The drive between these members and the cans is not positive, slippage being caused by the brushes 22. Hence a scrubbing action is imparted through the brushing element to the can side walls. The cans in being moved around the interspace between the arcuate

frame 7 and the wheel 13 are passed endwise between the brushes 22 which scrub the opposing ends thereof clean. As the cans reach the end of their arcuate path, those which are 5 passing therealong thrust those ahead along the curved portion 6 of the trough and back onto the conveyor 1 from which they are carried to the labeling machine.

What I claim as my invention is—

10 In a can washing machine, a driven wheel having opposed flanges, a guide spaced from the periphery of the wheel, said wheel flanges and the guide co-acting to support and rotate the cans, and means for brushing the exterior 15 surfaces of the cans.

Dated at Vancouver, B. C., this 4th day of April, 1929.

WILLIAM HOWARD RENNIE.
